UNITED STATES PATENT OFFICE.

JOANNIN BOUËT, OF KIDDERMINSTER, ENGLAND, ASSIGNOR TO JOSEPH WILD & CO., OF NEW YORK CITY.

DESIGN FOR A CARPET-PATTERN.

Specification forming part of Design No. 5,327, dated October 31, 1871.

To all whom it may concern:

Be it known that I, JOANNIN BOUËT, of Kidderminster, in the county of Worcester, England, have invented a new and original Design for a Printed Carpet, of which the following is a specification:

The nature of my design is fully represented in the accompanying sketch, to which reference is made.

I claim as my invention—

The design for a carpet, as shown.

JOANNIN BOUËT.

Witnesses:

JAMES MORTON,
U. S. Consular Agent, Kidderminster.

CHARLES FROST,
Clerk to Mr. Morton, Kidderminster.
